UNITED STATES PATENT OFFICE.

HAROLD S. OSBORNE, OF NEW YORK, N. Y., ASSIGNOR TO AMERICAN TELEPHONE AND TELEGRAPH COMPANY, A CORPORATION OF NEW YORK.

COMPOSITE SIGNALING-CIRCUITS.

1,314,828.

Specification of Letters Patent. Patented Sept. 2, 1919.

Application filed June 8, 1917. Serial No. 173,527.

To all whom it may concern:

Be it known that I, HAROLD S. OSBORNE, residing at New York, in the county of New York and State of New York, have invented 5 certain Improvements in Composite Signaling-Circuits, of which the following is a specification.

This invention relates to telephone repeater circuits and more particularly to two-way, 10 two-repeater circuits associated with composited telephone and signaling lines. Its object is to protect the telephone repeater from the signaling currents, and to provide means for conducting the signaling current 15 around the telephone repeater station without impairing the impedance balance necessary for repeater operation.

The invention is best understood by reference to the accompanying drawing which 20 is a diagram of a two-way, two-repeater system embodying the arrangements of my invention.

Referring to the accompanying drawing a telephone and telegraph transmission line 25 is divided into two sections 1 and 1' at a telephone repeater station. The telephone repeater is of the well-known two-way two-repeater type and comprises two similar and equal parts R and R'. Line section 1 is 30 connected at terminals 3 and 4 to an electric wave filter 5. Said wave filter is a connecting or artificial line comprising a plurality of sections, each section having a condenser 6 in series with each side of the line and two serially connected inductances 7, 7 in 35 shunt across the line, the common terminals of each pair of serially connected inductances being connected to ground by conductor 8. The properties of the wave filter 40 are fully described in U. S. Patent 1,227,113 of May 22, 1917, to G. A. Campbell, wherein it is shown that a filter consisting of serial capacity and shunt inductance, transmits with negligible attenuation all currents of 45 frequency above a preassigned inferior limit while attenuating and substantially extinguishing all currents of frequency less than said inferior limit. It will be observed that filter 5 consists of two similar halves sym- 50 metrically related to ground and for this reason I have termed said filter a duplex filter. The function of filter 5 is two-fold. First, it prevents low frequency signaling currents from entering the repeater apparatus while at the same time freely transmit-

ting the relatively high frequency telephonic currents. Secondly, by virtue of its duplex structure and ground connections, it prevents the flow of signaling current from one side of the line to the other, and thus largely 60 eliminates interference between composited signaling sets associated with the same telephone circuit.

Filter 5 is connected through transformer 9 to repeater circuit 10, said circuit comprising two serially connected similar and equal coils 11, 11 of a three coil transformer 12, a coil 13 of a two coil transformer 14, connected from the common point of coils 11, 11 to the other side of the circuit, and a coil 15 of a transformer 16, similar and equal to transformer 9. Coil 17 of transformer 14 is connected to the receiving element of repeater 18, while coil 19 is serially connected to the output circuit or transmitting 75 element of repeater 18.

For repeater operation, it is essential that the impedance connected to the terminals of coil 20, consisting of filter 5 and line 1, shall be accurately balanced or simulated by 80 the impedance connected to the terminals of coil 21 of transformer 16. To this end it is customary to provide an artificial line 22, which may be of any of a number of forms well known to the art, whose impedance 85 closely simulates the impedance of line 1. Since, however, line 1 is connected to coil 20 by filter 5, my invention provides an equivalent filter 23 which connects artificial line 22 to coil 21. It will be evident that 90 said arrangements provide for proper impedance balance of line 1 and filter 5 providing that artificial line 22 proper balances line 1, and that the circuits are symmetrical with respect to circuit 10. While I have 95 illustrated filter 23 as of the duplex type and having the common point of each pair of serially connected inductances 24, 24 connected to ground by conductor 25, it is not essential that said filter be of the duplex 100 type or have a ground connection. In fact each pair of serially connected inductances 24 and 24 might be equally well replaced by a single inductance element whose inductance is equal to twice that of each coil 24. 105

When lines 1 and 1' serve not only as a metallic telephone circuit but as the conductors of two composited ground-return telegraph circuits, means must be provided for conducting the telegraph currents past 110

the telephone repeater; that is, shunt the telegraph current from lines 1 to 1' and from line 1' to line 1. This may be done in accordance with this invention by connecting 5 terminals 3 and 3' by a conductor 26 containing one or more retardation coils 27, 27 and similarly connecting terminals 4 and 4' by a conductor 28 containing one or more retardation coils 29, 29, preferably similar and 10 equal to coil 27.

This creates a mutual connection between lines 1 and 1' so that part of the telephone currents impressed from line 1' through the repeater upon line 1 can flow back through 15 coils 27 and 29 to line 1' thereby causing a distortion of the telephone currents which would be detrimental and if great enough would cause the repeater to sing. This effect may be eliminated in accordance with 20 this invention, however, by connecting terminals 30 and 30' of artificial lines 22 and 22' through one or more retardation coils 31 and 31, similar and equal to coils 27, and likewise connecting terminals 32 and 32' 25 through one or more retardation coils 33 and 33, similar and equal to coils 29, so that the effect on the repeater of currents flowing through coils 27 and 29 is counteracted by the effect of equal and opposite currents 30 flowing through coils 31 and 33.

It will thus be seen that this invention may be applied in any case where it is desired to prevent the tendency of telephone repeaters to sing because of a mutual action between 35 the incoming and outgoing lines, whether due to terminal apparatus of any sort, or to the proximity of the lines themselves. In other words the tendency to sing may be counteracted by creating between the two 40 artificial lines a mutual action equivalent to that between the line sections themselves.

What is claimed is:

1. In a two-way two-repeater system, two transmission line sections, two artificial 45 lines individually associated with said line sections, a broad band wave filter connecting

each line section with the repeater apparatus and two similar wave filters similarly connecting said artificial lines with said repeater apparatus.

2. In a two-way two-repeater system, a 50 composed transmission line, a two-way two-repeater station dividing said line into two sections, two artificial lines individually associated with said line sections, apparatus 55 in shunt with said repeater station connecting said line sections, and apparatus associated with said artificial lines for duplicating therein the effect of the shunt apparatus on the lines.

3. In a two-way two-repeater system, two transmission line sections, a repeater interconnecting said lines, two artificial lines associated with said repeater and said line sections, means for causing an interaction between said line sections, and means for producing an equivalent interaction between the 60 artificial lines.

4. A composite transmission system, comprising metallic telephone line sections, each 70 side of said line sections being used as a telegraph circuit, a repeater interconnecting said sections, conductive paths extending from each side of one of said line sections to corresponding sides of another line section 75 and in shunt with said repeater, means in said paths to permit the transmission of telegraph currents but substantially preventing the transmission of telephone currents, balancing net works associated with said repeater for balancing each line section, and conductive paths between said balancing net works for simulating the electrical characteristics of said first mentioned paths.

In testimony whereof, I have signed my 85 name to this specification in the presence of two subscribing witnesses, this 19th day of May, 1917.

HAROLD S. OSBORNE.
